United States Patent Office.

WILLIAM KNOWLES, OF ROCKVILLE, INDIANA.

Letters Patent No. 80,187, dated July 21, 1868.

IMPROVEMENT IN SHAWL-PINS.

The Schedule referred to in these Letters Patent and making part of the same.

TO ALL WHOM IT MAY CONCERN:

Be it known that I, WILLIAM KNOWLES, of Rockville, in the county of Parke, and State of Indiana, have invented a new and useful Improvement in Shawl-Pins; and I do hereby declare that the following is a full, clear, and exact description of the same, reference being had to the annexed drawing, making part of this specification, in which it is shown in perspective.

The pin consists of three arms, A, B, and C, united at the middle by a band, D, to which they are all soldered. The central arm, B, extending on each side of the band, is bent at the points as shown, and sharpened. The outer arms, A and C, after passing through the band D, are bent outwardly on each end, and then extending parallel with the arm B, are in like manner bent at the point and sharpened. All the points on each side are in line with one another.

The pin is attached by drawing together the shawl, and hooking the points on each side, when the pin will be held in place by the tension of the shawl.

What I claim as my invention, and desire to secure by Letters Patent, as a new article of manufacture, is—
A shawl-pin constructed of the bent arms A, B, and C, attached to the band D, substantially as described.
In testimony whereof, I have signed my name to this specification in the presence of two subscribing witnesses:

WILLIAM KNOWLES.
